TRIPLEX BOARD USED IN PATHOLOGY

Joseph Navara, 2105 Walton St., Chicago, Ill. 60622

Filed Mar. 13, 1970, Ser. No. 21,885

Term of patent 14 years

Int. Cl. D24—02

U.S. Cl. D83—1

FIG. 1

FIG. 2

FIG. 3

FIG. 4

FIG. 5

FIG. 1 is a top plan view of a triplex board used in pathology, showing my new design;

FIG. 2 is a side elevation thereof;

FIG. 3 is an end elevation thereof;

FIG. 4 is an elevation taken from the opposite end of FIG. 3; and

FIG. 5 is an exploded perspective view of the triplex board.

I claim:

The ornamental design for a triplex board used in pathology, as shown.
